VIBRATION DAMPENER FOR PIPES

Arthur N. Wells, 2028 Belle Monti Ave., Belmont, Calif.

Filed June 21, 1962, Ser. No. 70,643

Term of patent 14 years

(Cl. D91—3)

FIG. 1.

FIG. 2.

FIG. 3.

FIG. 4.

FIG. 5.

FIG. 6.

FIG. 1 is a perspective view of a vibration damper for pipes, showing my new design;

FIG. 2 is a bottom plan view;

FIG. 3 is an end elevation thereof as seen from the opposite end of FIG. 1;

FIG. 4 is a perspective view of a modified form of the vibration damper for pipes disclosed in FIGS. 1-3 inclusive, wherein the end portion thereof is substantially flush, rather than recessed, and is symmetrically contoured to receive a pipe;

FIG. 5 is a bottom plan view of the modification shown in FIG. 4; and

FIG. 6 is an end elevation of the modification shown in FIG. 4 as seen from the opposite end of FIG. 4.

The dominant features of my design reside in the portions shown in full lines.

This application is a continuation-in-part of my application Serial No. D. 61,549, filed July 27, 1960 and now abandoned.

I claim:

The ornamental design for a vibration damper for pipes, as shown and described.
